UNITED STATES PATENT OFFICE.

ANDREW L. LEWIS, OF PETERSBURG, VIRGINIA.

PUMP.

Application filed June 30, 1922. Serial No. 571,885.

To all whom it may concern:

Be it known that I, ANDREW L. LEWIS, a citizen of the United States, residing at Petersburg, in the county of Dinwiddie and

5 State of Virginia, have invented new and useful Improvements in Pumps, of which the following is a specification.

This invention relates to foot operated pumps and proposes a construction in which 10 the reciprocating pumping mechanism is actuated by the weight of the operator.

One of the objects of the invention is the provision of a pump having a reciprocating plunger operating under different loads on 15 the up and down strokes, said plunger being actuated by the weight of the operator, exerted alternately to force said plunger to perform its upward and downward movements, there being means to apply the full 20 weight of the operator to that stroke of the plunger operating under the greater load and to impress but a component of said weight upon that stroke which operates against the lighter load.

25 More specifically the object of the invention is to provide a reciprocating-plunger pump which lifts a column of liquid by suction upon the up stroke of the plunger and forces its discharge upon the down stroke, 30 in which it is presumed that the discharge load is greater than the suction load, with foot rests working on opposite sides of a fulcrum or pivot, one of said foot rests being connected directly to the plunger rod 35 and arranged to move vertically downward under the weight of the operator, and the other being connected to said plunger rod to draw it upwardly and arranged on an inclined plane so that only a component of 40 the weight of the operator is applied to lift the plunger.

With the above and other objects in view, my invention consists in the improved pump illustrated in the accompanying drawings, 45 described in the following specification, and particularly claimed, and in such variations and modifications thereof as will be obvious to those skilled in the art to which my invention relates.

50 In the drawings accompanying and forming a part of this specification, and wherein the preferred embodiment of my invention is illustrated:

55 Figure 1 is a side elevation, partly in section showing my improved pump installation.

Figure 2 is a plan view of the same.

Figure 3 is a cross section taken along the line 3—3 of Figure 1.

Figure 4 is a side sectional view on an 60 enlarged scale of a portion of the cylinder.

Figure 5 is a side elevation of a detail of the pump operating mechanism showing one 65 foot rest and Figure 6 is a side view, partly in section of the other foot rest.

Referring now in detail to the several figures, the numeral 1 represents a well provided with the platform 2 upon which rests the pump base 3, having, depending therefrom the cylinder 4, the lower end of which 70 dips below the water level 5. It is of course not essential that the lower end of the cylinder be submerged, but in the type of pump shown in the illustration it is presumed that the cylinder is within sufficient distance of 75 the surface of the water to permit the actuation of the pump by atmospheric pressure.

Within the lower end of the cylinder is the check valve 6, shown in Figure 4, and a discharge conduit 7 communicates with 80 the cylinder above said check valve and is provided with the faucet 8 and with another discharge outlet 9 which may be connected to a hose or other piping and led to a remote point. For the carrying out of the 85 present invention it is presumed that the power required to discharge liquid from the pump will be greater than that necessary in lifting the water column from the well.

The plunger 10 of the cylinder is connected to a plunger rod 11, the top of which is provided with a cap 12 having an eye 13 formed therethrough to which is attached a rope or cable 14, the latter passing over a pulley 15 which is pivotally mounted in 90 the upper horizontal limb 16 of a frame formed of channel iron and having inclined sides 17 and 18 fixedly anchored to the ground at their lower ends as shown at 18 in Figure 1.

A bracket 19, Figures 1 and 5 is secured to one side of the plunger rod and supports a foot rest 20. When the operator of the pump stands upon the foot rest 20 the plunger rod 11 is forced downwardly into 95 the cylinder and the plunger 10 performs its discharge stroke.

The rope or cable 14 passes down from the pulley 15 between the flanges of the channel 18 where it is secured to the foot rest 21 105 by being passed through an aperture 22 in the back of said foot rest and secured in

a loop as shown in Figure 6. The foot rest 21 is supported upon an angular bracket 23 the side 24 of which slides against the bottom 25 of the channel 18, being held in sliding relation thereto by a bolt 26 passing through the side 24 of said bracket and a slot 26' in the bottom of said channel, a pair of washers 27 and 28 being arranged on said bolt outside of said relatively sliding members and held in place by the nut 29. When the operator stands upon the foot rest 21 the plunger rod is drawn upwardly, the plunger performing its suction stroke.

A step 30 is provided on the platform 15 2 upon which the operator mounts preparatory to placing his feet upon the foot rests 20 and 21.

The check valve 6, shown in Figure 4, seats upon a flat annular valve seat 31 formed in a depression 32 on the inner side 20 of a bushing 33. This bushing forms the lower end of the cylinder 4, with which it is in threaded engagement, and has an up-standing annular flange 34 surrounding the 25 check valve 6 and of slightly greater diameter than said check valve, the flange 34 being also spaced a slight distance from the wall of the cylinder 4. A pin 35 extends across the flange 34 being secured to opposite sides thereof and forms a limit stop 30 for determining the extent of opening movement of said valve. The flange 34 is provided with ports 36 which are adapted to 35 permit a lateral flow into the annular space between said flange and the wall of the cylinder; sufficient to supply the demands of the outlet conduit 7, by having the valve 32 travel within the vertical guideway

formed by the flange 34 and slightly spaced from the wall thereof. The outlet into the cylinder is restricted increasing the velocity of the water flowing into said cylinder and insuring that gravel or other sedimentary matter will not lodge or collect upon the valve seat 31.

The space between the flange 34 and the wall of the cylinder functions as a trap to catch the sedimentary particles scraped from the walls of the cylinder from time to time by the plunger 10, preventing such matter 50 from falling upon the check valve. The ports 36 opening into this narrow annular space permit a relatively violent circulation of water in said space flushing it of said 55 deposits, which are discharged by way of the conduit 7.

It will be understood that various changes may be made in the form and relation of parts to suit different requirements of use, and that the invention, therefore, is not 60 limited to the precise details of construction and arrangement shown.

Having described my invention what I claim as new and desire to secure by Letters 65 Patent, is:—

A pump comprising a cylinder, a reciprocatory plunger working in said cylinder, a plunger rod, a foot rest secured to said plunger rod, a pulley, a second foot rest, and flexible means passing over said pulley 70 for securing said second foot rest to said plunger rod.

In testimony whereof I have hereunto set my hand.

ANDREW L. LEWIS.
